ATTORNEYS.

UNITED STATES PATENT OFFICE.

ALBERT WANNER, JR., OF HOBOKEN, NEW JERSEY.

DESIGN FOR A MIRROR-FRAME.

SPECIFICATION forming part of Design No. 25,279, dated March 24, 1896.

Application filed October 14, 1895. Serial No. 565,696. Term of patent 7 years.

To all whom it may concern:

Be it known that I, ALBERT WANNER, Jr., of Hoboken, in the county of Hudson and State of New Jersey, have invented and produced a new and original Design for a Mirror-Frame, of which the following is a full, clear, and exact description.

Reference is to be had to the accompanying drawing, forming a part of this specification, which represents a front view of a mirror, the frame of which embodies my new design.

The invention relates to mirror-frames and similar articles, and the leading feature of my design consists in the foliated scroll forming the leg *a*, presenting a substantially plain **S**-scroll, having a floriate spray *a'* running along one of its edges. These legs consisting of foliated scrolls, as described, appear on the

frame shown as disposed along the borders of the frame members and arranged in pairs, 20 adjacent legs forming pairs of ornaments being in reversed position. Thus the ornaments at the adjacent edges of the frame member at the center combined form lyre-figures. At the bottom of the frame the legs are disposed 25 vertically below the lower marginal edge of the frame proper.

I claim—

1. The design for a mirror-frame herein shown. 30
2. In the design for a mirror-frame, the leg herein shown.

ALBERT WANNER, JR.
